UNITED STATES PATENT OFFICE

2,007,702

SAFETY CONTROL APPARATUS

Frederick D. Austin, Port Chester, N. Y.

Application January 19, 1934, Serial No. 707,411

17 Claims. (Cl. 200—142)

This invention relates to improvements in the general type of safety devices of my United States Letters Patent No. 1,910,944, and No. 1,910,945, both dated May 23, 1933, and of my co-pending applications, one Serial No. 630,742, and the other Serial No. 630,743, both filed August 27, 1932. Subject matter of invention disclosed but not herein claimed is claimed in one or the other of said co-pending applications.

10 The primary object in view is improvement of the dependability and efficacy of the safety device to function accurately and to avoid accidental or undesired operation.

15 A more detailed object is the protection of a thermally-responsive fuse controlling an electric circuit from injurious influence of the electric current.

20 Another object is to afford such protection of such a fuse where the fuse is not normally responsive to current overload.

25 A still further object is the protection of such a thermally-responsive fuse against disintegration or disruption whether occurring slowly or suddenly under the action of an electric current.

30 In greater detail, a further object is the retention of a circuit breaker against circuit breaking action by a heat-responsive fuse.

An important object achieved by the present invention is the capacity of the improvements to be utilized in units already in use without structural modifications of such units.

35 Other objects will become apparent and obvious from the drawing and the description herein-after given.

35 In the various safety devices of the above-mentioned patents and pending applications there is used a fuse which is not ordinarily responsive to normal current load, or to a reasonable degree of current overload, but, since the

40 fuse in such devices is in the circuit, it is subjected to the action of current stresses, and, in some instances through current overload, as from a high starting torque of the controlled motor, or from other causes (such as a short circuit), may

45 be injured and thus caused to disrupt undesirably and not incident to thermic conditions; and the present invention contemplates providing all the advantages of the several control devices of the said patents and pending applications while preserving the thermic fuse entirely independent of current action, so that current overload or other deleterious effect on the thermic fuse is obviated.

50 In other words, the thermic-responsive fuse is by the present invention limited to its function of indicating the presence of abnormal thermic con-

ditions when it fuses, and the abnormal current load must be indicated by other apparatus forming no part of the present safety control device.

5 So far as the present invention is concerned, the same identical parts as shown in my said patents and co-pending applications may be utilized for illustrative disclosure, or the invention may be applied to various other combinations where a circuit is governed according to thermic conditions.

10 In the accompanying drawing,—

Figure 1 is a sectional elevation of a structure embodying the features of the present invention.

15 Figure 2 is a perspective view of the fuse unit and contiguous parts segregated and a fragment 15 only of the carrying bar for said parts being shown.

20 Figure 3 is a longitudinal, vertical section through a protecting sleeve applied to the parts of Figure 2, parts being seen in elevation, and 20 the parts being in the position after disruption of the fuse.

Figure 4 is a vertical cross section taken on the plane indicated by line 4—4 of Figure 3.

25 As illustratively applied in the accompanying drawing, the parts are substantially identical with those shown in Figures 1 and 2 of the drawing of my copending application Serial No. 630,742, above mentioned, but with the present improvements incorporated.

30 Referring to the drawing by numerals, 1 indicates a standard electric fitting consisting of a pronged insulating carrier having a right angle armor shield 2 to receive any of the well known armored electric cables with multiple wires. The 35

35 prongs of the fitting 1 are removably inserted in an insulating handle 3, which is provided with the customary sockets for receiving the prongs from the part 1 and directing them into contact with the outer terminals of electrical conductors 40

40 4. The conductors 4 extend throughout the length of an insulating bar or rod 5 which extends from the end of and is preferably formed integral with the handle 3, the outer end of the rod adjacent the handle being provided with threads 45

45 (shown in my last-mentioned copending application) for being detachably threaded into a metallic shell or casing 7. The shell 7 at its outer end is preferably provided with a nut-like or poly-sided handle 8 adapted to receive a wrench or 50 other tool for rotating the shell into operative position. The shell is provided with threads 9 adjacent the handle 8, which threads are preferably of the pipe thread type so as to be properly received in any appropriate pipe coupling or fit- 55

ting. The shell 7 is preferably, as seen in Figure 1, imperforate and closed at its inner end so as to prevent moisture from reaching the contained parts when the shell 7 is surrounded by moisture. 5 The outer end portion of the shell is internally threaded to receive the thread of the bar 5. The conductors 4 are preferably in the form of rods of resilient material so as to be capable of being sprung toward each other and to normally spring 10 apart as seen in Figure 3. The bar 5 is provided with passageways for the rods 4 after the manner shown in my last-mentioned co-pending application, which passageways preferably are widened to produce a single slot 10 at the inner 15 or free end of the bar so as to enable and provide for ample spring action of the rods 4.

The free terminals of the rod 4 are preferably flattened or otherwise rendered polysided, as plainly seen at 11, 11, in Figure 2, and are held in 20 a state of tension by a heat-responsive fuse unit which may be of the form shown in any of my above identified patents and co-pending applications, or otherwise as found preferable so long as capable of retaining the bars 4 against spring- 25 ing apart until the fuse is disrupted by a dangerously high temperature. An excellent illustrative instance of an appropriate form of such fuse is the type seen in Figure 2 of the drawings of my co-pending application Serial No. 630,742, which 30 fuse is shown in the accompanying drawing. This fuse is made up of plates 12, 12, and an interposed film of fusing material. Each of the plates 12 is provided with a sleeve 14 to receive the respective terminals of rods 4 and the sleeves 35 are shaped to snugly receive the flattened terminals 11 and thus prevent the plates 12 from rocking or pivoting on the rods 4 when the fuse gives way and allows the parts to move apart under the expanding tension of the rods 4 to the 40 position seen in Figures 3 and 4.

The plates 12 are preferably made of relatively thin sheet metal, such as copper, and the fusing material is preferably as thin as is practicable for resisting fusing under heat up to the degree 45 previously determined, and, to that end, the film of fusing material is preferably in the nature of solder applied as a thin solder coat between the two sheets 12, as fully set forth in my last-mentioned co-pending application.

50 The fuse member made up of the plates 12, the interposed film of fusing material therebetween, and the sleeves 14 may be variously otherwise constructed so as to give the required fusing action, and, when the present improvements 55 are employed, it is not at all necessary that the plates 12 be made of metal so long as they carry sufficient metal to provide for a fusible connection therebetween, and the sleeves 14 may well be made of insulating material so that no cur- 60 rent whatever can pass between the rods 4 through the fuse. This, however, is a matter of preference, since, as will become obvious, the provision of the present improvements obviates the passage of current through the fuse even 65 though metal be used for making up the sleeves 14 and plates 12.

Since contact must be provided between the rods 4 in order that the circuit may be retained closed during operation, any of various arrangements 70 may be employed whereby electric contact is established and retained between the rods 4, so long as the fuse is not disrupted. Any appropriate projection from one rod toward the other proportioned and located to cause electric contact between the rods, when the rods are

drawn sufficiently closely together to receive the sleeves 14, will suffice providing an adequate breaking of contact is assured when the bars 4 spring apart, as seen in Figure 3, on the disruption of the fuse. But I preferably provide for as perfect electric contact as possible between the two rods 4 and as complete and quick disruption of such contact as reasonably practicable to prevent arcing when separation of the rods occurs. To this end, an illustrative and at present preferred embodiment includes the parts as seen in the accompanying drawing wherein a unit or member similar in general contour and appearance to the fusing unit, except for the absence of fusing material and the presence of 10 spring action of the plates, is utilized. This contact unit thus preferably consists of two plates 13, 13, each carried by a sleeve 14', one of the sleeves being mounted on the flattened portion 11 of one rod 4, while the other sleeve is mounted on the similar portion of the other rod 4, so that, when the parts are drawn together and held by the fusing unit, as seen in Figure 2, the plates 13 will be in face contact and will afford electrical contact between the rods. The plates 13 and sleeves 14' with their connecting parts are all of electric conducting material, and the plates 13 are preferably of spring material and are sufficiently resilient to spring from the flattened condition seen in Figure 2 to the slanting positions seen in Figure 4 when the plates are released to separate. The plates are also preferably plated or coated with non-corrosive material, such as chromium, or made of non-corrosive material, to resist wear and injury. By providing for the slight springing action thus seen, when the plates are in the position seen in Figure 4 and are brought together to the position seen in Figure 2, the edgewise sliding action of each plate on the plate with which it contacts, which must occur as the plates move together, assures a clean and effective electrical contact.

Numerous other specific embodiments of the contact producing member or members between the rods 4 will readily suggest themselves, and 45 may be substituted while providing the results and applying the principles of the present invention.

The operation will be readily understood from the foregoing, and consists essentially in applying 50 a fuse unit to the projecting end portions of the bars 4 after the contact unit is in place. Naturally, a reverse order of these units is possible, but that stated is preferred, where the sleeves 14 are not of insulating material, so as 55 to cause the contact unit to be nearer the source of current and thereby offer a path of low resistance relieving the fuse from possibility of deterioration under current stresses. Of course, where the sleeves 14 are of insulating material, 60 the relative location is not important, except for convenience of applying a new fuse unit after disruption of one in use. It is also important that a sufficient and clean cut spacing of the plates 13 must occur immediately on disruption 65 of the fuse.

By the provision of the present invention the function of the safety control fuse for guarding against dangerous thermic conditions is not only assured, but freed from confusion with possible current action. A separate fuse unit must be provided to guard against current overload or other current defects, if such defects are to be taken care of, and, therefore, the operator will not expect of the present fuse unit any safety 75

against overload or other current conditions that are undesirable, except that all current will be cut off and operation stopped whenever a dangerously high temperature is threatened.

5 In the practicing of the inventions of my several above-identified patents and applications where surrounding, insulating sleeves have been employed to safeguard against short-circuiting incident to either the presence of accumulation 10 of fused material or other conditions, the sleeves have been found to be highly satisfactory and effective for the purpose, except that in some instances a sleeve has been too loose to retain itself in position on the insulating bar 5, and in a few 15 instances the loss of the sleeve has resulted in defective operation, so that it has become desirable to guard against such loss. To this end, the bar 5 is preferably formed with an annular groove 15 at the place of the normal location of the outer end of the protecting sleeve 16. The bar 5 is formed of hard rubber, or other appropriate insulating material, and the sleeve 16 is formed of similar material and has each of its ends turned inward to provide an annular 20 constriction or flange 17 proportioned to seat snugly in the annular groove 15 when the sleeve is slid onto the bar 5 to the position indicated in Figure 3. There is a slight springing action 25 and expansion of the sleeve in being moved to and from this position, and the resiliency is sufficient to effectively lock the sleeve 16 against accidental detachment from the bar 5 when the parts are in the position seen in Figure 3. Since a flange 17 is present at each end of the 30 sleeve, and the sleeve is otherwise a hollow cylinder, either end may be applied to the bar 5 when the parts are being assembled. The resistance to the necessary expansion of the sleeve to allow the same to slide into or away from the position seen in Figure 3 is not sufficient to 35 render such movement difficult, but is sufficient to insure retention of the sleeve during use and when the bar 5 is being handled outside of shell 7.

While the invention is shown applied in use 40 in one of my preferred embodiments known as an adapter, it is obviously applicable wherever it is desirable to control the operation of a furnace or other heat source, and to stop such operation on reaching a dangerously high temperature. The lead wires (not shown) which extend into the part 2 are, of course, connected to the controlling motor or other controlling parts to supply current thereto, so that, when the circuit is broken, as indicated in Figure 3, there is a cessation of opportunity for increase 45 in temperature. The operator must renew the fuse before the apparatus governed by the current passing through the conductors or rods 4 will operate again. This renewal is preferably 50 accomplished by first withdrawing the sleeve 16 longitudinally, and then longitudinally withdrawing the plates 12 with their sleeves 14, drawing the rods 4 toward each other until the plates 13 are moved from the position seen in Figure 4 55 to the position seen in Figure 2, and then sliding a fuse unit onto the rods 4 to the position seen in Figure 2 so that the contact between the rods 4 established by the plates 13 will be maintained.

70 While it is obvious from the drawing of this application, as well as from the disclosure of the above-mentioned patents and applications, that the present invention is well adapted for controlling the current to the fuel supply motor or for otherwise controlling the combustion of a

furnace incident to the water level thereof, it should also be apparent that other parts may be similarly controlled and that the temperature change governing the responsiveness of the fuse may be caused to be felt by the unit otherwise than through the drop of the liquid level. 5

The sleeve 16 is of hard rubber, gutta percha, or fiber or other appropriate insulating material, and the flanges 17 may be formed thereon in any desired manner, as by turning or spinning 10 the terminal edges of the sleeve over to the flanged condition after the sleeve has been otherwise completed.

Since the inner extremity of the shell 7 is located in the least cooled area of the adapter, I 15 have found that at times, if the sleeve 16 be imperforate and open only at its ends, the heat developing within the sleeve occasions a substantial pressure and sometimes the fuse of the fusing unit 12 is disrupted prematurely owing 20 to such pressure and heat. To insure better circulation of air and thus relieve the pressure, and also to allow distribution of heat more nearly directly from the area surrounded by the sleeve 16, I provide vents or apertures 18, 18, located 25 about the sleeve and in the length of the sleeve at sufficiently frequent intervals to enable the cooling effect of the water which surrounds the shell 7 to be sufficiently felt within the area surrounded by sleeve 16 to avoid premature 30 disruption of the fuse.

What is claimed is:

1. In safety control devices, the combination, with electrical conductors movable relatively to each other, of a thermally-responsive fuse 35 physically and electrically connecting the conductors to retain them against relative movement, and means additional to the fuse electrically connecting said conductors while the conductors are thus held by said fuse. 40

2. The combination as claimed in claim 1 wherein the additional means electrically connecting said conductors is independent of the fuse.

3. The combination as claimed in claim 1 45 wherein the additional means electrically connecting said conductors is independent of and spaced from the fuse.

4. The combination as claimed in claim 1 50 wherein the additional means electrically connecting said conductors is independent of and spaced from the fuse in the direction toward the source of current.

5. The combination as claimed in claim 1 55 wherein the additional means for electrically connecting said conductors comprises separable parts adapted to be separated and thus to break electrical contact between the conductors when the conductors are moved.

6. The combination as claimed in claim 1 60 wherein the conductors are tensioned under resilient stress tending to move the same to contact breaking position when not held by the fuse.

7. The combination as claimed in claim 1 65 wherein the conductors are tensioned under resilient stress tending to separate the conductors to a circuit breaking position when the conductors are not held by the fuse.

8. The combination as claimed in claim 1 70 wherein the means electrically connecting said conductors comprises plates in face contact with each other and carried by the respective conductors.

9. The combination as claimed in claim 1 75 wherein the means electrically connecting said

conductors comprises plates in face contact with each other and carried by the respective conductors, the plates being tensioned under resilient stress tending to force the plates away from each other.

10. The combination as claimed in claim 1, wherein the means electrically connecting said conductors comprises plates in face contact with each other and movable apart, and a sleeve for each of the plates, one of the sleeves surrounding one of the conductors and the other sleeve surrounding the other conductor.

11. The combination as claimed in claim 1, wherein the means electrically connecting said conductors comprises plates in face contact with each other and movable apart, and a sleeve for each of the plates, one of the sleeves surrounding one of the conductors and the other sleeve surrounding the other conductor, each of the conductors having a flattened portion and each of the sleeves having a flattened portion engaging the flattened portion of the respective conductor and thus preventing angular movement of the respective plate with regard to its conductor.

12. In safety control devices, the combination, with a pair of resilient conductors tensioned to spring apart when released and a fuse physically and electrically connecting and restraining said conductors against separation, of metal plates electrically connected to said conductors independent of the fuse and in face contact while the conductors are thus held by the fuse, the said plates being proportioned to be separated from electrical contact under the movement of the conductors when released by the fuse.

13. The combination, with conductors adapted

to be disposed in an electrical circuit, of a thermally-responsive fuse physically and electrically connecting and retaining the conductors against relative movement under normal temperature conditions and while the fuse is preserved against disruption from high temperature, and means closing the circuit between said conductors while the conductors are thus retained, said means being proportioned and adapted to cause the circuit to be broken between the conductors when the conductors move on being released by the fuse incident to disruption of the fuse.

14. The combination, with movable conductors and a control fuse therefor retaining the conductors in operative relation, of an insulating bar carrying said conductors, an insulating sleeve surrounding said fuse and detachably surrounding a portion of said bar, there being between the sleeve and bar a frictional connection comprising a projection extending from one and a recess in the other receiving said projection, whereby the sleeve must expand in moving to and from a seated position on the bar.

15. The combination as claimed in claim 14, wherein the recess is an annular groove in the bar and the projection is an inwardly-extending terminal flange on the sleeve.

16. The combination, with conductors and a control fuse therefor, of an insulating bar carrying said conductors, and an insulating sleeve surrounding said fuse and detachably engaging said bar, the sleeve being laterally vented.

17. The combination as claimed in claim 16, wherein the sleeve has its end open opposite that engaging the bar.

FREDERICK D. AUSTIN.
